UNITED STATES PATENT OFFICE.

EDWIN FERGUSON TITCOMB AND CHARLES HENRY PETERS, OF DENVER,
COLORADO.

PAINT-OIL.

SPECIFICATION forming part of Letters Patent No. 389,946, dated September 25, 1888.

Application filed September 24, 1887. Serial No. 250,546. (No specimens.)

To all whom it may concern:

Be it known that we, EDWIN FERGUSON TITCOMB and CHARLES HENRY PETERS, both citizens of the United States, residing at Denver, in the county of Arapahoe and State of Colorado, have invented a certain new and useful Composition of Matter to be Used as Paint, of which the following is a specification.

Our composition consists of the following ingredients, combined in the proportions stated, viz: crude petroleum, twelve parts; boiled linseed-oil, four parts; spirits of turpentine, three parts; naphtha, three parts. These ingredients are to be thoroughly mingled by agitation.

In using the above named composition it may be colored with any of the vegetable or mineral coloring-matters, and may be applied in the same manner as ordinary paint.

By the use of the above composition a good even coating of lasting material is obtained at greatly reduced cost.

What we claim, and desire to secure by Letters Patent of the United States, is—

The composition of matter for a paint compound or vehicle, consisting of crude petroleum, linseed-oil, turpentine, and naphtha, combined in about the proportions substantially as set forth.

In testimony whereof we affix our signatures in presence of two witnesses.

EDWIN FERGUSON TITCOMB.
CHARLES HENRY PETERS.

Witnesses:

A. BALLMAN,
CHAS. LOW.
